UNITED STATES PATENT OFFICE.

EUGENE S. TOWNS, OF AUSTIN, TEXAS.

BORING MACHINE.

Application filed July 19, 1921. Serial No. 485,837.

To all whom it may concern:

Be it known that I, EUGENE S. TOWNS, a citizen of the United States of America, and resident of Austin, in the county of 5 Travis and State of Texas, have invented certain new and useful Improvements in Boring Machines, of which the following is a specification.

This invention relates to metal working 10 machines, and particularly to a machine adapted for use in dressing cylinders of internal combustion motors without removing the block or cylinder from the crank case; the said invention being effective to operate 15 in conjunction with cylinders by the simple removal of the cylinder heads, the pistons and connecting rods of two adjacent or adjoining cylinders, means being provided for anchoring the machine in one of the cylinders, 20 whereby it may be held in operative relation to the cylinder to be dressed.

A still further object of this invention is to provide novel means for holding the tool carrying element in rotatable relation to the 25 cylinder wall, and the provision of novel means whereby the tool may be fed longitudinally of the cylinder while being rotated; the said invention furthermore contemplating the provision of means for centering the tool with relation to the cylinder wall by means which can be readily applied to or removed from its operative position with relation to the said cylinders.

With the foregoing and other objects in 30 view, the invention consists in the details of construction, and in the arrangement and combination of parts to be hereinafter more fully set forth and claimed.

In describing the invention in detail, reference will be had to the accompanying 35 drawings forming part of this application, wherein like characters denote corresponding parts in the several views, and in which—

Figure 1 illustrates a view in elevation of a machine embodying the invention;

Figure 2 illustrates a view in elevation of the tool and its mounting;

Figure 3 illustrates a plan view partly in section of the cutter drive;

Figure 4 illustrates a plan view of a cutter mounting;

Figure 5 illustrates a top plan view of the frame of the device and the parts associated therewith;

Figure 6 illustrates a sectional view of the tool mounting;

Figure 7 illustrates a detail view of the means for adjusting the tool mounting with relation to the anchoring device;

Figure 8 illustrates a detail view of the tool mounting support;

Figure 9 illustrates a plan view thereof.

Figure 10 illustrates a side view of a slide block for the lower centering pin of the 65 tool mounting; and

Figure 11 is a side elevation of the upper centering pin.

In these drawings 10 denotes the head frame having suitable bearings for a shaft 70 11 of a gear wheel 12, and a bearing 13 for a shaft 14 carrying a pinion 15 which meshes with the gear wheel 12, the said shaft being designed as the drive shaft to receive power from a crank handle or power transmitting means such as a belt or sprocket chain. As the means for applying power to the drive shaft 14 is an immaterial detail, it need not, it is thought, be shown specifically.

The shaft 11 has a toothed wheel 16 on its lower end which meshes with the teeth of the wheel 17 which is formed with or connected to the tool mounting 18. The tool mounting is preferably of cylindrical construction having a seat 19 at its upper end and a seat 20 at its lower end to form bearings, and this tool mounting may be termed a "boring bar" in that it is rotatably mounted and carries the tool, as will presently appear. The head frame has a depending spindle 21 of conical shape fitted in the seat 19 formed in the upper end of the tool mounting. The spindle is threaded in the head frame and the conical configuration of its lower end serves to properly center the tool mounting. The gear 16 is wider than the gear 17, a condition which permits a limited vertical adjustment of the tool carrier while maintaining the engagement 90 of these gear wheels which are provided for communicating the power from the drive shaft through the train of gearing to the tool mounting.

A head stock 22 has a slotted arm 23 to receive an anchoring element 24 in the nature of a screw or the like, attached to the head frame, and by this arrangement, the head stock may be moved toward or away 100 from the head frame, and these parts may be 105

110

held in proper spaced relation to each other by the fastening 24, in order that the head stock may be placed in a cylinder and anchored, as will presently appear, to retain 5 the cutter mounting centered with relation to the adjacent cylinder which is to be treated. A tail stock 25 is intended to contact with the head stock 22, the head stock 22 being intended to enter the cylinder at the 10 top, and the tail stock being intended to enter the cylinder at the bottom. The head stock has a stud 26 threaded in it, and this stud extends through the tail stock, its lower end being threaded, as shown at 27 to engage 15 a nut 28 by which the head and tail stocks are clamped in the cylinder. The said head and tail stocks are conical to facilitate the centering of these elements with relation to the cylinder to which they are applied.

20 The tail stock 25 has a slotted arm 29 in which a seat 30 is adjustably secured by the nut 31. The seat is intended to support the lower spindle 32 which projects into the seat 20 of the tool mounting 18, in order that the 25 tool mounting may be free to rotate under the influence of the driving mechanism heretofore described.

25 As stated, the tool mounting 18 is of cylindrical construction and it has a recess 33 in one side extending practically throughout its length, in which a screw 34 is rotatably mounted by reason of the fact that said screw has a bearing at its lower end in the end of the tool mounting, as shown at 35.

30 The screw is also journaled at its upper end through the head of the tool mounting, as shown at 36, and a star wheel 37 is secured to the said screw. The screw 34 is, of course, a feed screw and it is intended to move the 35 tool as the cutting action progresses. In this embodiment of the invention, the cutter 38 is carried by a ring 39 which encircles the cylindrical member, the said ring having a web 40 extending into the recess 33. The 40 web is apertured, as shown at 41, and its walls are engaged by the screw 34 so that as the screw is rotated, the ring 39 will be moved longitudinally of the cylinder to feed the tool during its cutting operation.

45 As furthermore shown in this embodiment of the invention, the slidable tool carrier is provided with a seat for a set screw 43 which has a conical end for engagement with the beveled end of the cutter 38, and a seat for a set screw 45 that clamps the cutter in place, and it may be noted that the internally threaded apertures intersect the opening in which the cutter is seated, and that the inward extending portion of the cutter carrier 50 by engagement with the longitudinal walls of the recess in the tool carrier prevents rotation of the slidable tool carrier and provides a housing for the screw 34.

55 The star wheel is caused to engage a trip 44 as it is carried around with the tool

mounting, and it is moved the distance of one tooth of the said star wheel at each rotation of the tool mounting, although the feeding operation could be increased by adding trips to operate the star wheel more frequently, but that is a condition which those skilled in the art will understand without further illustration of the same.

60 It will be apparent from the description and illustration that the head and tail stocks may be readily applied to a cylinder, and that the tool supporting trunnions or spindles may be adjusted with relation to the head and tail stocks, and the manner of driving the mechanism or operating it, will be understood from the fact that a description of the function and operation of the parts and their relation to one another has been stated in connection with a description of the elements comprising the present embodiment of the invention.

65 The boring tool hereinbefore described is particularly adapted for use in reborning cylinders of internal combustion engines, and with such engines the pistons do not have a stroke equal to the entire length of the cylinders, consequently the cylinders are true at their ends, and by using a pair of cylinder engaging members with conical portions the head and tail stocks adjust or aline themselves when clamped in position for use. The length of the tool mounting is such relative to the head stock that the cutter carrier may be moved beyond the conical portion of the head stock and entirely beyond the cylinder to be trued, and provision is made for a lateral adjustment of the tool mounting and the cutting tool.

70 I claim:

75 1. In a machine for boring cylinders, a pair of conical heads which are adapted to be positively connected and held in engagement with opposite ends of a cylinder, laterally extending members carried by the heads, laterally adjustable center pin carriers maintained by the laterally extending members of the heads, a tool mounting engaged by pins which are supported by the pin carriers, and means for rotating the tool mounting associated with one of the heads.

80 2. A boring machine comprising a pair of head stocks each having conical portions for engagement with the end portions of a cylinder, centrally located means for clamping the head stocks in positive engagement with a cylinder, lateral extending members integral with their respective heads, laterally adjustable centering pins maintained by the laterally extending members, a tool mounting maintained by the pins and provided with a gear, driving means associated with one of the head stocks for engagement with the gear on the tool mounting, and a cutting tool slidably associated with the tool mounting.

3. In a boring tool a pair of conical cylinder end engaging members, means for connecting said members and clamping them in positive engagement with the opposite ends 5 of a cylinder, laterally projecting members having slots therethrough said members being integral with the aforesaid cylinder end engaging members, a frame adjustably secured to one of the slotted members, a centering point carried by the frame, a train of gears operatively associated with the frame, a tappet that projects from the frame, a tool mounting provided with a gear which is driven to rotate the tool mounting, a feed 10 screw carried by the tool mounting and provided with a star wheel that engages the tappet during the rotation of the tool mounting, a centering pin in adjustable engagement with the opposite end of the tool mounting 20 and a traveling cutter carrying ring associated with the tool mounting and its feed screw.
4. In a tool for boring cylinders, a pair of cylinder engaging members each having conical portions for engagement simultaneously with opposite ends of a cylinder, one of the heads being of greater length than the other, a centrally located bolt for connecting the heads, means associated with the heads for maintaining a tool mounting in position 25 to operate within an adjacent cylinder, a cutter carrying frame on the tool mounting such frame being movable on the tool mounting beyond the end of the cylinders. 30

EUGENE S. TOWNS.
